UNITED STATES PATENT OFFICE.

WILLIAM J. DIEDRICH, OF WAUKESHA, WISCONSIN.

DEVICE FOR KILLING INSECTS.

1,178,139.

Specification of Letters Patent.

Patented Apr. 4, 1916.

Application filed August 16, 1915. Serial No. 45,784.

To all whom it may concern:

Be it known that I, WILLIAM J. DIEDRICH, a citizen of the United States, residing at Waukesha, in the county of Waukesha and 5 State of Wisconsin, have invented certain new and useful Improvements in Devices for Killing Insects, of which the following is a specification, reference being had to the accompanying drawings:

10 This invention relates to an improved insect killing device and has for its primary object to provide a simple and effective means for killing flies and like insects, the device being so constructed as to eliminate 15 the necessity of swinging the arm, in order to strike the fly with the implement.

It is more particularly the object of the invention to provide a device for the above purpose, embodying a handle member having 20 a spring pressed pivoted hammer mounted therein, a flexible steel blade fixed at one end to the hammer and provided upon its other end with a wire screen plate, and means for causing a rapid vibration of said 25 steel blade, when the hammer is released.

It is an additional object of the invention to provide a fly killing device which is in 30 the form of a toy pistol and will, therefore, afford a certain degree of amusement to juveniles, the device as a whole being exceedingly simple in its construction and, 35 therefore, capable of manufacture at comparatively small cost.

With the above and other objects in view, 40 my invention consists in the novel features of construction, combination, and arrangement of parts to be hereinafter more fully described, claimed, and illustrated in the accompanying drawing, in which,

45 Figure 1 is a perspective view illustrating the manner of using my invention; Fig. 2 is an enlarged longitudinal section; Fig. 3 is a perspective view of a slightly modified form of the device.

50 Referring in detail to the drawing, 5 designates the handle which is in the form of the handle usually provided upon cap pistols and the like. This handle is of hollow construction and, in the top wall of the 55 same, adjacent to its forward end, a slot 6 is formed, through which the head of the hammer 7 projects. This hammer head normally extends longitudinally of the slot 6 and, at its forward end, a recess 8 is formed in the lower face thereof to receive the longitudinally projecting shoulder 9, at the for-

ward end of the slot 6. The hammer 7 is pivotally mounted upon a transverse pin 10 fixed at its ends in the opposite side walls of the handle 5 and the shank 11 of said hammer extends through the hollow handle and projects outwardly through a longitudinal slot 12 formed in the lower wall of the handle 5.

The forward end of the head of the hammer 7 is provided with a kerf or slot, in which one end of the flexible steel spring plate 13 is fixed. To the other or free end of this spring plate, the wire screen head 14 is secured, said screen head being normally 70 disposed in spaced relation to the forward end of the handle 5.

The hammer 7 is held in its normal position by means of a leaf spring 15, arranged within the hollow handle 5. One end of 75 this leaf spring is engaged against an internal lug 16 formed upon the butt end of the hollow handle. The spring extends longitudinally within the handle and over a pin 17, which is spaced from the lug 16, said 80 spring bearing against the opposite side of the pin, with respect to the side of the lug which is engaged by the extremity of the spring. The other end of the leaf spring 15 bears against a shoulder 18 formed upon the 85 head of the hammer 7. It will be understood from this construction that when the hammer 7 is drawn back to the position shown in Fig. 1, so that the spring plate 13 is disposed in an approximately vertical 90 position, the free end of the leaf spring 15 is forced downwardly and said spring is placed under tension. Upon the release of the hammer the spring 15 acts to throw the hammer head and the spring plate 13 downwardly and violently engage the wire screen head 14 on the free end of the spring, upon 95 the fly or other insect.

For the purpose of causing a snapping or vibration of the spring plate 13, I provide 100 on the top wall of the hollow handle 5, at its forward end, a raised flange or lug 19, with which said spring plate contacts.

In the use of the device as above described, 105 the operator securely grasps the handle 5 in one hand and with the thumb draws back the hammer head 7, thereby placing the spring 15 under tension, as above explained. When the device has been properly located with respect to the fly or other insect which 110 it is desired to kill, the hammer is released so that the wire head 14 is forcibly projected

downwardly and upon the fly, thereby killing the same. It will be observed that by means of my device, swinging movements of the arm, which are required in all ordinary devices heretofore provided for this purpose, are rendered unnecessary so that the fly is given no warning of the approaching danger or otherwise frightened away. The invention will, therefore, be very reliable 10 and effective in practical use.

In Fig. 3 of the drawing, I have shown a slightly modified form of the device, wherein the use of the pivoted spring pressed hammer is dispensed with and the flexible 15 steel spring plate 13' is fixed at one of its ends, directly to the handle member 5'. The forward end of this member is in spaced relation to the fixed end of the spring plate and is provided with a raised flange or rib 20 19', in the same manner as in the preferred embodiment of the invention. In the use of this latter construction, the operator grasps the handle 5' in one hand and, with the finger of the other hand, raises the outer 25 free end portion of the spring plate 13'. When the wire mesh head on the end of said spring has been disposed over the fly, the spring plate is released so that upon its return to normal position, the wire head will 30 be engaged upon the insect with sufficient force to kill the same.

From the foregoing description, taken in connection with the accompanying drawing, the construction and manner of operation of 35 the several described embodiments of my invention, will be clearly and fully understood. Both constructions are quite simple, may be easily and quickly operated and provide effective and reliable means for killing 40 the insects. It will be understood that the wire mesh head on the free end of the flexible spring plate may be of any desired size or shape. When the spring plate loses its resiliency, a new one may be readily attached 45 to the pivoted hammer head or to the handle 5'. While I have disclosed what I believe to be the simplest mounting and arrangement of the pivoted hammer and the spring, for operating the same, it is to be borne in mind 50 that such features of the device may be con-

siderably modified and that the present invention is not limited to such specific structural details as are shown in the accompanying drawing. The invention is also susceptible of many other changes in the form, proportion and arrangement of the several elements and I, therefore, reserve the privilege of adopting all such legitimate modifications as may be fairly embodied in the spirit and scope of the invention, as claimed. 60

What is claimed, is:—

1. In a device of the character described, a handle provided with an upstanding rib on one end, and a flexible spring plate carried by said handle and projecting over said 65 rib and beyond the forward end of the handle, the forward extremity of said plate having a striking head fixed thereon, said spring plate being adapted for engagement upon said upstanding rib, whereby the plate 70 is caused to vibrate.

2. In a device of the character described, a handle member, a pivoted spring pressed hammer mounted in said handle member, and a flexible spring plate fixed at one end 75 to the hammer and projecting beyond the forward end of the handle, said spring plate having a striking head fixed upon its free end.

3. In a device of the character described, 80 a handle, a spring pressed hammer mounted in the handle, a flexible steel plate fixed at one of its ends to the hammer, said spring plate normally extending longitudinally of the handle and projecting beyond the forward end thereof, a striking head fixed upon 85 the free end of said spring plate, said plate being adapted to be raised to an approximately vertical position, when the hammer is cocked, and an upstanding rib formed on the forward end of the handle with which 90 said spring plate is adapted to engage, when the hammer is released, whereby said plate is vibrated.

In testimony whereof I hereunto affix my 95 signature in the presence of two witnesses.
